UNITED STATES PATENT OFFICE.

WILLIAM N. SLEICHER, OF TROY, NEW YORK.

DESIGN FOR AN ANCHOR-YOKE FOR NON-SKID CHAINS.

59,384.

Specification for Design.

Patented Oct. 11, 1921.

Application filed March 27, 1920. Serial No. 369,445. Term of patent 14 years.

To all whom it may concern:

Be it known that I, WILLIAM N. SLEICHER, a citizen of the United States of America, residing at Troy, in the county of Rensselaer and State of New York, have invented a new, original, and ornamental Design for an Anchor-Yoke for Non-Skid Chains, of which the following is a specification, reference being had to the accompanying drawing, forming part thereof.

The single figure of the drawings is a view in perspective showing an anchor-yoke for non-skid chains embodying my design.

I claim:

The ornamental design for an anchor-yoke for non-skid chains, as shown.

WILLIAM N. SLEICHER.
